WITNESS:

ATTORNEY

UNITED STATES PATENT OFFICE.

JACOB E. POPOFF, OF CAMBRIDGE, MASSACHUSETTS.

TARGET.

Application filed February 10, 1925. Serial No. 8,267.

To all whom it may concern:

Be it known that I, JACOB E. POPOFF, a citizen of the United States, residing at Cambridge, in the county of Middlesex and 5 State of Massachusetts, have invented new and useful Improvements in Targets, of which the following is a specification.

This invention relates to a game, the general object being to provide a plurality of 10 objects arranged upon a casing and when hit with a projectile will cause the same to move within the casing and close a circuit at the destination thereof whereby lamps of varying or different colors will be illuminated.

Another object of the invention is to provide a tripping means upon the upper portion 15 of the casing which when operated moves laterally within the casing whereby the destination of an object within the casing may be changed and pre-determined before its traveling.

A further object of the invention is to provide electric conducting means upon one 20 side of the casing and which may be readily and easily associated with a separate casing in order that a plurality of casings may be arranged in series and yet be electrically connected with the first mentioned casing in 25 order that a plurality of circuits will not be necessary.

With the above and other objects in view, the invention further includes the following 30 novel features and details of construction, to be hereinafter more fully described, illustrated in the accompanying drawings and 35 pointed out in the appended claims.

In the drawings:

Figure 1 is a top plan view of the casing 40 with parts broken away and showing the arrangement of the tripping means and channels arranged within the casing.

Figure 2 is a transverse section taken 45 through one of the channel members and casing and showing the relative position of the elements therein.

Figure 3 is a sectional view of the ends or 50 sides of a pair of casings with the electrical connecting means therefor.

Figure 4 is a plan view of the projectile 55 means and showing the operation of the same.

Figure 5 is a diagrammatic plan view of 60 the electrical circuit used in conjunction with the present invention.

Referring to the drawings in detail, wherein like characters of reference denote corresponding parts, the reference character 10 indicates a casing proper which includes a transparent panel which extends vertically 60 upon the upper side thereof and adjacent the rear end thereof. The front of the casing 10 has positioned therein a plurality of substantially U-shaped grooved channels having their yoke ends arranged in coacting relation and the channel portions as at 12 in Figures 1 and 2 of the drawings and are shown in plan view in Figure 2 of the drawings as set and supported at an inclination toward the front of the casing proper 70 the grooved channels, including spacing blocks 13 upon the under sides thereof and which are of varying heights in order that the said channel portions 12 may be held and supported at the inclination as 75 aforementioned.

Positioned upon opposite sides and adjacent the forward end portion of the channel members 12 are pairs of contact members 14, one of each being connected through suitable conducting wires 15 to lamp bulbs 16 which may be of any desired color and are positioned directly behind the vertically extending transparent panel 11 arranged upon the upper side of the casing 10. Conducting wires 17 and 18 are connected to the companion sides of the lamp bulbs 16 and opposite contact members 14 respectively; the conducting wire 18 is connected to a battery or the like 19 as indicated in Figure 5 90 of the drawings.

It will thus be noted that upon bridging the space between the spaced contacts 14 that the circuit will be closed and the lamp bulbs 16 may be selectively illuminated. In 95 order to provide means, in the form of the object, for closing the circuit or bridge the space between the spaced contact members 14, I provide metallic ball members 20 which are preferably hollow and which are so 100 shaped as to readily and easily fit within the grooved portions 12 and easily travel therein.

As mentioned in the foregoing, relevant 105 to the means included between the channelled portions 12 arranged within the casing 10 or predetermining the destination of the ball members 20, that is, in just which channel portion 12 the ball 20 will travel, I provide a shaft member 21 which has its lower 110

end portion journaled within a block member arranged directly behind the channel members 12 and which has its opposite end extending through and above the top of the 5 casing 10 and includes a substantially U-shaped bar member 23 thereon, which has included upon the free end portions thereof, disk members 24; rigidly secured upon the shaft 21 within the casing 10 is a switch 10 25 which includes curved portions 26 upon opposite sides and adjacent the free end portions thereof and which are adapted to be swung laterally between the channel members 12 and form one wall thereof in order 15 that the passage of the ball members 20 within the channel members 12 will be restricted to one channel only.

As inferred and understood from the detailed description and accompanying drawings, it is plausible that upon rendering the casing 10 as a target it would be necessary to provide projectile means for operating the target. To this end I provide a bow 27 which includes an apertured lug member 28 upon the intermediate portions thereof and which is adapted to be pivotally secured or positioned upon a plate member 29 in order that the bow 27 will be held in position and against accidental displacement 30 whereby the same will be always in position and ready for use. The projectile means includes an arrow 30 which of course has its inner end portion engaging a bow string or the like 31 and when fitted thereon and pulled rearwardly against the tension of the bow 27, it will be noted that the bow will be caused to bend and allow the projectile in the form of the arrow 30 to be shot outwardly therefrom and the player 35 of this game will aim to hit the disk members 24 in order to predetermine the passage of the ball members 20 within the channel members 12 before aiming at the ball members 21 to cause the same to be rotated or 40 travel within the channel members 12 in order to engage the selective contact members 14 arranged at the outer ends thereof, in order that lamps 16 of varying colors may be illuminated.

50 As mentioned in the foregoing, as to providing connecting means between a plurality of casings, I extend plug members 32 between the corresponding sides of the respective casings and which plug members 55 have secured to the outer end portions thereof conducting plates 33 and which have included thereon binding posts 34 which are connected with a suitable conducting wire 35 leading to the next casing.

60 As clearly illustrated in Figures 1 and 2 of the drawings, cutout portions 36 are provided in the front of the casing 10 communicating with the ends of the channel members 12 in order that a portion of the ball members 20 will extend therethrough 65

so that the projectile member 30 may easily and readily hit its mark and send the object, being the ball member 20, in its course of travel within the channel members 12 in order that the spaced contact members 14 70 may be bridged and the circuit closed in order that the lamps 16 may be selectively illuminated.

The invention is susceptible of various changes in its form, proportions and minor details of construction, and the right is herein reserved to make such changes as properly fall within the scope of the appended claims.

Having thus described my invention what is claimed is:

1. A target of the character described comprising a casing, a plurality of channeled horseshoe shaped members arranged within the casing and tilted forwardly 85 therein, switch members included between the horseshoe members, means included upon the upper portion of the switch means for moving the same laterally therein, spaced contact members arranged adjacent the forward end portions of the horseshoe members and electric signalling means connected in circuit with the contact members for registering a shot.

2. A target of the character described comprising a casing, a plurality of forwardly extending cross section channel shaped interconnected horseshoe members arranged therein and having registering openings provided in the front of the casing adjacent the ends thereof, pairs of spaced contact members arranged within the casing between the openings and the end portions of the horseshoe members and upon opposite sides of the ends thereof, switch members arranged between the interconnecting portions of the horseshoe members and having the opposite sides thereof curved to resemble the side wall of the channels, means provided upon the upper portion of the casing and connected with the switches whereby the same may be easily and readily turned to simultaneously turn the switches, ball members arranged within the channels and normally bridging the space between a pair of the contact members and extending forwardly an appreciable distance through the openings provided in the front of the casing, a plurality of lamp bulbs arranged upon the rear of the casing and connected with the contact members, projectile means for moving the ball members within the channel portions, and electric connecting means included between the side walls of the casings whereby the same may be connected with a plurality of similar casings arranged in parallel therewith.

In testimony whereof I affix my signature.

JACOB E. POPOFF.
